(57) **CLAIM**

We claim the ornamental design for a stent, as shown and
described.

DESCRIPTION

FIG. 1 is an upper perspective view of a stent;

FIG. 2 is a lower perspective view thereof;

FIG. 3 is a front elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions of the Figures shown in broken lines are for
illustrative purpose only and form no part of the claimed
design.
